US0D1004198S

(12) **United States Design Patent** (10) **Patent No.:** **US D1,004,198 S**
(45) **Date of Patent:** **** Nov. 7, 2023**

(54) **SHAVING RAZOR**

- (71) Applicant: **The Gillette Company LLC**, Boston, MA (US)
- (72) Inventors: **Philipp Goeder**, Frankfurt (DE); **Jonathon Albert Riehle**, Brighton, MA (US); **Jack Anthony Washington**, Mendon, MA (US)
- (73) Assignee: **The Gillette Company LLC**, Boston, MA (US)
- (**) Term: **15 Years**
- (21) Appl. No.: **29/863,085**
- (22) Filed: **Dec. 15, 2022**

Related U.S. Application Data

- (62) Division of application No. 29/738,830, filed on Jun. 19, 2020, now Pat. No. Des. 977,718.
- (51) **LOC (14) Cl.** **28-03**
- (52) **U.S. Cl.** **D28/46**
- (58) **Field of Classification Search**
- USPC D28/46-48
- CPC B26B 21/14-38; B26B 21/52-528

(57) **CLAIM**

The ornamental design for a shaving razor, as shown and described.

DESCRIPTION

FIG. 1 is a front perspective view of the first embodiment of a shaving razor showing our new design;
FIG. 2 is a front view thereof;
FIG. 3 is a rear view thereof;
FIG. 4 is a right view thereof;
FIG. 5 is a left view thereof;
FIG. 6 is a top view thereof;
FIG. 7 is a bottom view thereof;
FIG. 8 is a rear perspective view thereof;
FIG. 9 is a front perspective view of the second embodiment of a shaving razor showing our new design;
FIG. 10 is a front view thereof;
FIG. 11 is a rear view thereof;
FIG. 12 is a right view thereof;
FIG. 13 is a left view thereof;
FIG. 14 is a top view thereof;
FIG. 15 is a bottom view thereof; and,
FIG. 16 is a rear perspective view thereof.

The broken lines shown in FIGS. 1-8 illustrate a portion of the shaving razor and form no part of the claimed design.

1 Claim, 10 Drawing Sheets
